(57) **CLAIM**

The ornamental design for a combined periodontal sulcus brush head and intrasulcular medicament applicator, as shown and described.

DESCRIPTION

FIG. 1 is a top, right side, and front perspective view of a first embodiment of a combined periodontal sulcus brush head and intrasulcular medicament applicator, showing my design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof; and

FIG. 7 is a bottom plan view thereof; and

FIG. 8 is a top, right side, and front perspective view of a second embodiment of a combined periodontal sulcus brush head and intrasulcular medicament applicator, showing my design;

FIG. 9 is a right side elevation view thereof;

FIG. 10 is a left side elevation view thereof;

FIG. 11 is a front elevation view thereof;

FIG. 12 is a rear elevation view thereof;

FIG. 13 is a top plan view thereof; and,

FIG. 14 is a bottom plan view thereof.

The broken lines shown in FIGS. 1-4, 5-11, and 13-14 illustrate portions of the combined periodontal sulcus brush head and intrasulcular medicament applicator that form no part of the claimed design.
